2,467,826

LIFTING SLIP-JOINT

Ira W. Henderson, Detroit, Mich., and Hans T. Nilsen, Mathews, Va., assignors to Raymond Concrete Pile Company, New York, N. Y., a corporation of New Jersey

Application February 5, 1947, Serial No. 726,658

2 Claims. (Cl. 61—78)

1

An object of this invention is to disclose ways and means for economically sinking into the ground concrete piles of unusual length under unusually difficult conditions. This invention is an improvement on that disclosed in Upson U. S. Patent No. 1,836,140.

In that patent the shell is made in sections, each larger in diameter than the one below it, and each adapted to surround one of the cylindrical steps of a drive core. Although the patent shows shell sections of different diameters the present invention applies just as well if the sections are of uniform diameters.

To save cost it is desirable to form the shell of as thin material as possible, which means that the shell must be pulled into the ground under tension instead of being pushed or driven down under compression. In order to reduce wear and tear of the soil on the shell sections, a rigid ring of slightly greater diameter than the shell section, is provided to plow a path for each section. Since the shell must have sufficient rigidity to withstand the compression of the surrounding earth after the core is removed and before the concrete is poured, the metal of the shell is preferably corrugated, thereby providing the necessary resistance against crushing.

Shoulders on the drive core are utilized to push down the plow rings and the plow rings serve to pull down the shell sections.

Under certain difficult conditions, such as driving through clay into hardpan, it has been found that some of the bottom shell joints pull apart due to heaving of the ground, allowing water and mud to enter the shell. To overcome that difficulty the present inventors conceived the idea of inserting, at an appropriate point in the shell, a combination lifting slip-joint strong enough, and rigid enough, to hold the shells together and in alignment during shelling-up and other handling operations, but weak enough to slip longitudinally if the upper part of the shell heaves.

There are two plow rings in the joint, each having upwardly and downwardly extending annular fins. The upper fin of the inner ring is attached to the bottom of a shell section, and has its lower fin attached to a downwardly extending corrugated screw collar which is threaded into the upper end of the next lower shell section. The collar has only two or three corrugations, and the gauge of the material is lighter than that of the shell sections.

The upper end of the lower shell section has attached to it the other plow ring. To the upper fin of that ring is attached a plain cylindrical

5 sleeve extending upwardly around the lower end of the shell section above it with packing between the sleeve and the shell. The corrugated screw collar serves to hold the shell together during all handling and shelling-up operations, and then, should the ground heave, this collar slips over the corrugations of the shell section, and the upper plow ring leaves the lower ring, the lower end of the whole shell being anchored in the hardpan. But no harm is done because the entry of mud and water is prevented by a tubular sleeve and packing, inserted between the sleeve and the shell.

10 Further and other objects and advantages will be apparent from the specification and claims, and from the accompanying drawings which illustrate what is now considered the preferred embodiment of the invention.

In the drawings:

15 Fig. 1 shows a driven shell incorporating the invention;

20 Fig. 2 is an enlarged sectional view showing the invention in detail.

25 In Fig. 1 the shell has been driven into ground 10. The shell comprises corrugated sections 12, 14, 16, 18 and 20, each larger in diameter than the one below it. Sections 14 and 16 are joined together by the structure of the invention, which will be described in detail. The other sections 30 are provided at their lower ends with plow rings 22, 24, 26 and 28, each slightly larger in diameter than the shell section to which it is attached. A plate 30 closes the bottom of the shell.

30 Referring to Fig. 2, 32 is a tubular drive core having a shoulder 34 resting on the upper side of plow ring 36, which has an upper fin 38 attached to the lower end of shell 16, and a lower fin 40 to which is attached the top of a short corrugated collar 42 of comparatively light gauge metal, and screwed into the top of shell 14.

35 Underneath ring 36 is a somewhat similar ring 44 having a downwardly extending fin 46 connected to the top of shell section 14, and an upwardly extending fin 48 attached to the bottom 45 of a tubular sleeve 50 which extends upwardly outside of, and closely adjacent to, the lower end of shell section 16.

40 The space between shell 16 and sleeve 50 is calked with packing 52, thus preventing passage 55 of water or mud. Should the joint be subjected to sufficient stress to raise ring 36 from ring 44, the corrugations of collar 42 will deform sufficiently to slip relatively to shell 14, but no water or mud will enter the shell past sleeve 50. It is to be understood that the invention is not

limited to the specific embodiment herein illustrated and described but may be used in other ways without departure from its spirit as defined by the following claims.

What is claimed is:

1. Means for joining upper and lower adjacent corrugated sections of a shell for a concrete pile, comprising in combination, a plow ring at the bottom of said upper section, a corrugated collar extending downwardly from said ring and 10 screwed into the top of said lower section, a ring at the top of said lower section and in contact with the underside of said first-mentioned ring, and a tubular sleeve extending upwardly from the top of said lower section and surrounding the bottom of said upper section.

2. Means for joining upper and lower adjacent corrugated sections of a shell for a concrete pile, comprising in combination, a plow ring at the bottom of said upper section, a corrugated collar 20

extending downwardly from said ring and screwed into the top of said lower section, a plow ring at the top of said lower section and in contact with the underside of said first-mentioned ring, a tubular sleeve extending upwardly from the top of said lower section and surrounding the bottom of said upper section, and waterproof calking between said sleeve and said upper shell section.
